UNITED STATES PATENT OFFICE.

EDWARD CRAIG, OF ST. JOSEPH, MICHIGAN.

MULTIPLE-HEAD STAPLING-MACHINE.

1,381,617.

Specification of Letters Patent. Patented June 14, 1921.

Application filed April 30, 1917. Serial No. 165,542.

To all whom it may concern:

Be it known that I, EDWARD CRAIG, a citizen of the United States of America, and resident of St. Joseph, Berrien County, Michigan, have invented a certain new and useful Improvement in Multiple-Head Stapling-Machines, of which the following is a specification.

My invention relates to fastener-driving-machines in general, but more particularly to machines for inserting fasteners in sheet-material to hold the same together, and especially to stapling-machines for inserting staples along one corner of pasteboard cartons or boxes, while the latter are still in the form of flat and folded blanks, whereby these blanks can be expanded into the shape of square tubes, having flaps which can thereafter be folded to close the opposite ends of each box or carton.

Generally stated, the object of my invention is to provide a novel and improved construction whereby a plurality of successive fastener-driving-operations may be performed on the work in a rapid and economical manner, thereby to reduce the cost of production of the boxes or other articles which require the insertion of staples or other fastening-devices therein.

More specifically considered, the object of my invention is to provide an improved construction and arrangement whereby the folded box-blank or other work to be stapled can be fed forward to a position where it will receive a row of staples from the fastener-driving-mechanism, and whereby the work can then be fed sidewise to receive another row of staples from the same mechanism, so that the two rows of staples will be parallel.

It is also an object to provide certain details and features of construction and combinations tending to increase the general efficiency and desirability of a multiple-head stapling-machine of this particular character.

To the foregoing and other useful ends, my invention consists in matters hereinafter set forth and claimed.

50 In the accompanying drawings:—

Figure 1 is a front elevation of the left-hand end-portion of a multiple-head stapling-machine embodying the principles of my invention.

55 Fig. 2 is an enlarged fragmentary perspective of a portion of the means by which

the work is guided to the position for receiving the staples or other fasteners.

Fig. 3 is a front elevation of the right-hand end-portion of the machine shown in Fig. 1.

Fig. 4 is an enlarged detail view of the ratchet and cam mechanism which controls the lateral or sidewise feed of the work, showing the ratchet in retracted position, 65 being an enlarged sectional view on line 4—4 in Fig. 21.

Fig. 5 is a similar view showing the ratchet in its forward actuated position.

Fig. 6 is a plan of the machine shown in Figs. 1 and 3.

Fig. 7 is a right-hand end-elevation of the machine shown in Figs. 1 and 3.

Fig. 8 is an enlarged detail section on line 8—8 in Fig. 6.

75 Fig. 9 is a plan view of the flat or unfolded blank from which the box or carton is made.

Fig. 10 shows the blank in its partially folded condition, after the staples are 80 driven therein, leaving the flaps unfolded at opposite ends of the box.

Fig. 11 is an enlarged detail sectional view on line 11—11 in Fig. 12.

Fig. 12 is a plan of the mechanism shown in Fig. 11.

Fig. 13 is a view similar to Fig. 11, but on a smaller scale, and showing the parts in different positions.

Fig. 14 is a view similar to Fig. 13, but 90 showing the parts in different positions, being a section on line 14—14 in Fig. 15.

Fig. 15 is a vertical section on line 15—15 in Fig. 14, and on line 15—15 in Fig. 12.

Fig. 16 is a view similar to Fig. 11, but 95 on a larger scale, and showing the parts in different positions.

Fig. 17 is an enlarged view of the clutch-mechanism shown at the right in Fig. 7.

Fig. 18 is a detail sectional view on line 100 18—18 in Fig. 17.

Fig. 19 is an enlarged transverse section on line 19—19 in Fig. 6, being also a section on line 19—19 in Fig. 21, but with the parts in different positions.

105 Fig. 20 is a vertical section on line 20—20 in Fig. 21.

Fig. 21 is an enlarged vertical longitudinal section on line 21—21 in Fig. 7.

Fig. 22 is a vertical section on line 22—22 110 in Fig. 21, showing the parts in certain positions.

Fig. 23 is a portion of Fig. 22, showing certain of the parts in different positions.

As thus illustrated, my invention comprises a frame or body 1 having a horizontal table 2 supported longitudinally thereon, and provided with parallel rods 3 extending at each side of said table, a little below the surface thereof, said table and rods being supported at the receiving end of the machine by uprights 4 of any suitable character. Transversely arranged sprocket-shafts 5 and 6 are mounted, respectively, at the discharge end and the receiving end of said table, and are provided with sprocket-wheels for engaging the endless sprocket-chains 7 which travel parallel and longitudinally of said table. These belts or chains are provided at intervals with cleats or engaging portions 8, which serve as pushers for feeding the work along said table. The body-frame is provided with uprights 9 and 10 which provide a support for the horizontal and longitudinal bar 11 upon which the staplers 12 are mounted, these staplers being arranged close together in a straight row. The uprights 9 and 10 provide bearings for the shaft 13 upon which are mounted the cam-devices 14 by which said staplers are operated, which latter can be of any suitable known or desired character. The straight row of staplers thus provided is arranged about midway between the two feed-belts 7, and parallel therewith, and directly above the horizontal and longitudinally extending clencher-bar 15, which latter is flexible and secured at one end to the guide-member 16 which is adjustably mounted on the end of the bar 11, being movable up and down by an eccentric or cam-device 17 having a handle 18 for the adjustment thereof, whereby this bar 15 is movable up and down to suit the requirements of the work. The guide-member 16 is provided with guide-slots 19 and 20 which receive the upper and lower flaps 21 and 22 of the folded blank (see Figs. 8, 9 and 10), so that the two flaps are delivered one on top of the other to the upper surface of the bar 15 during the forward feeding movement of the work. The parallel stationary guides 23 and 24 are arranged to extend parallel with the feed-belts at opposite sides thereof (see Fig. 6), to properly guide the folded blank into position to receive the first row of staples. The deflectors 25 and 26 serve to gradually depress the flap 21 until it enters the guide 19, and in a similar way the deflector 27 serves to depress the flap 22 onto the guide 28, which latter leads to the guide-slot 20, whereby the two flaps of the blank will be brought together. A transversely arranged rock-shaft 29 is mounted in suitable bearings on the frame, at the discharge end of the machine, and is provided with a crank-arm 30 connected by a rod 31 with the bell-

crank 32 which is pivoted at 33 on the block 34, which latter is adjustably secured by set-screws 35, or in any suitable manner, to the horizontal and longitudinally disposed rod 36, which latter is in turn supported by the bell-crank 37 and the arm 38, which are pivoted, respectively, at 39 and 40 on stationary portions of the body-frame. This rod 36 is threaded at 41 to receive the nuts 42 by which the position of the arm 38 on this rod is changed or varied to suit the requirements. A spring 43 is secured to the top of the block 34, at 44, and arranged to bear down upon the work, so that the flaps of the blank will be held one upon the other as the work travels forward to the stapling position below the staplers. A spring 45 connects the pivotal point 46 of the rod 31 on the bell-crank 32 with the bracket 47, so that the lower end-portion 48 of this bell-crank (this end-portion 48 serves as a stop for the pusher 8 on one of the feed-belts) tends to remain in normal position (see Fig. 11), and whereby this bell-crank is movable from this position against the tension of said spring. An arm 49 is also pivoted at 33, and has a short arm 50 provided with a pin 51 which engages the upper end-portion of the bell-crank 32 (see Figs. 11 and 13), and a roller 52 is mounted at the end of the arm 49 to bear upon the work, being disposed above a slot 53 in the table, immediately outside of the outer feed-belt. The rod 36 is square to prevent rotation of the block 34 thereon, but is cylindric where it is threaded at 41 for the adjustment previously described. When the two layers or thicknesses 54 and 55 of the folded blank are forced forward by the feed-belts to a point where their forward edges extend under the roller 52 (see Fig. 13), the arm 49 will be raised, and the pin 51 will tilt the bell-crank 32 into such a position that the stop 48 will be directly in the path of the pusher 8 which is propelling the blank forward at the rear edge of the latter. When the pusher 8 engages the stop 48, the bell-crank 32 is then tilted about its pivot 33 (see Fig. 16), causing the rod 31 to pull the arm 30 toward the staplers, causing the shaft 29 to be rocked in its bearings. For this purpose, the rod 31 is provided with an adjustable stop 56 for engaging the arm 30, but which permits the rod to slide in the end of the arm 30, in the opposite direction, without producing movement of this arm. Said rod 31 is also provided at its end with a handle 57 by which it can be manually manipulated to control the machine in certain ways. The shaft 5, it will be seen, extends across the delivery end of the machine, and is provided with a clutch 58 which controls the transmission of power to this shaft from the worm-gear 59, the latter being operated by spur-gearing which is in turn operated by the 130

sprocket-gearing 61 which has its sprocket-chain 62 connected with a sprocket on the main driving-shaft 63, the latter being mounted in suitable bearings at the top of 5 the body-frame, whereby this main shaft extends parallel with the feed-belts. The rock-shaft 29, which is parallel with and immediately above the sprocket-shaft 5, is provided with an arm 64 which is connected by 10 a link 65 with the toggle-joint-connection 66 between the pivoted clutch-shifter 67 and the stationary bracket 68, the arrangement being such that when this toggle-joint is raised, the shifter 67 operates to close the 15 clutch 58, thus causing a transmission of power from the shaft 63 through the sprocket-chain 62, through the gearing 60 to the worm-gearing 59, and from the latter through the shaft 5 to the two parallel feed-belts. On the other hand, when this toggle-joint 66 is depressed (see Fig. 17), said clutch is then opened, thereby stopping the operation of the feed-belts. The opening of 20 the clutch 58 occurs when the pusher 8 engages the stop 48, for the reason that this produces a pull on the rod 31, which causes the arm 30 to rock the shaft 29, thus depressing the arm 64 and causing the toggle 66 to operate the shifter 67 to open the clutch. 25 This stops the work directly beneath, the staplers 12, in position to receive the first row of staples, which latter are to be inserted through the two superimposed thicknesses of the blank.

30 At the same time that the automatic forward feed of the work is interrupted, in the manner described, the operation of the staplers 12 is automatically started, and the arrangement for doing this is as follows:

35 Assuming, for convenience of description, that the machine is already in operation, a cam-device 69 on the stapler-shaft 13 has a vertically reciprocating connection 70 to the lower end of which the shorter arm of 40 the bell-crank-lever 37 is pivoted at 71, so that this cam-device serves to reciprocate the rod 36 when it becomes necessary to raise the stop 48 out of the path of the pusher 8 on the feed-belt, thereby to permit said 45 pusher to pass said stop after the two rows of staples have been driven. With the arrangement shown, the stop 48 is raised each time the staple-drivers move downward, but this is only effective after the second row 50 of staples has been driven, as will hereinafter appear. This connection 70 has an opening 55 72 which engages the end-portion 73 of the lever 74, which latter is pivoted on the frame at 75, whereby this lever is tilted about its 60 pivot when the connection 70 moves up and down. The other end of this lever 74 is connected by a link 76 with the arm 77 on the short shaft 78, (see Figs. 4, 5, 20 and 21) 65 and a ratchet-pawl 79 is pivoted on this arm to engage the ratchet-wheel 80. (provided

with six teeth) on said shaft. When the connection 70 is actuated downward, and when the drivers of the staplers 12 move downward to insert the first row of staples, the lever 74 is tilted about its axis 75 to draw 70 the dog or pawl 79 backward over the ratchet-wheel 80, a band-brake 81 serving to hold the shaft 78 against rotation at this time. When the staple-drivers move upward, the connection 70 also moves upward, 75 thus tilting the lever 74 in the opposite direction, causing the pawl 79 to move forward (see Fig. 5), thus turning the shaft 78 one notch. The cam 82 is fixed on the shaft 78, adjacent said ratchet-mechanism, 80 and is formed with three equidistant projections for engaging the roller 83 on the member 84 which is slotted to reciprocate on the shaft 78, this member 84 being connected by a pitman-rod 85 with the pivoted arm 85 86, which latter is pivoted at 87 upon a stationary portion of the machine. This forward actuation of the ratchet causes one of the projections of the cam 82 to engage the roller 83, thus producing an upward 90 movement of the rod 85, so that the lateral feed-device or shifter 88 is operated by the pivoted arm 86 (the shifter 88 is disposed in line with the guide 23 to bear against one edge of the blank), and whereby the blank 95 is shifted sidewise under the staplers. The actuation of the pawl 79, by partially rotating the shaft 78, serves also to rotate the wheel 89 which is fast on said shaft, so that the three notches of this wheel (see Fig. 22) 100 assume an intermediate position relative to the projection 90 on the upper edge of the pivoted arm 91, the latter being pivoted at 92 upon the stationary portion of the machine. The shaft 29 is provided with a laterally extending arm 93 connected by a link 94 with said pivoted arm 91, so that when this shaft 29 was rocked by the rod 31, in the manner previously described, the arm 91 was pulled downward to disengage the 105 projection 90 from one of the notches of the wheel 89, thus unlocking the shaft 78, and at the same time closing the clutch 95 which controls the transmission of power from the main driving-shaft 63 through the gears 96 110 to the stapler-shaft 13, thereby starting the operation of the staplers. It will be seen that this clutch, which may be of any suitable character, is connected by a link 97 with the lever 91, so that said clutch is closed to start the staplers when the shaft 29 is rocked by the engagement of the pusher 8 with the stop 48 previously described. Now when the staple-drivers move upward (after driving the first row of staples), causing the partial rotation of the wheel 89, the connection 70 operates the bell-crank 37, as 115 previously explained, thereby returning the stop 48 from its raised position to a position behind the pusher 8 (see Fig. 14), and 120

125

130

it is during this idle movement of the stop 48 and the upward movement of the staple-drivers that the lateral or sidewise feed-device 88 is actuated to push the partially stapled blank sidewise and into position to receive the second row of staples. Also, at this time (while the stop 48 is in elevated position), the clutch 95 is held closed and the clutch 58 held open by the engagement of the roller 98 which engages a cam 99 on the shaft 13, so that the staplers are retained in operation and the rock-shaft 29 held by the said roller and cam against rocking backward to close the clutch 58, for the latter must be retained open to prevent the operation of the feed-belts. This roller 98, it will be seen, is mounted on the lever 100 which is pivoted at 101 to a stationary portion of the machine, and to the lower end 20 of which the link 97 is pivoted. The clutch 95, which controls the transmission of power from the gearing 96 to the shaft 13 (one of the gears 96 being loose on the shaft 13) is provided with a spring-pressed key 102, in 25 the splined member of the clutch, and when this key is actuated by its spring, it engages the loose member of the clutch and closes the transmission between the gearing and the shaft. (This is a well-known form of 30 clutch.) The lever 100 has a beveled portion 103 for operating the key 102, (see Fig. 3) and when the shaft 29 was rocked by engagement of the pusher 8 with the stop 48, as previously explained, the lever-arm 91 35 was pulled downward, and the lever 100 was tilted to permit the bevel 103 to disengage the bolt 102 (see Fig. 22 and dotted lines in Fig. 23), thus closing the transmission 40 of power to the stapler-shaft. The shaft 13 commences to rotate immediately (see arrows in Figs. 7, 22 and 23), and the cylindric peripheral portion of the cam 99 continues 45 to hold the roller 98 in the position shown in dotted lines in Fig. 23, so that the clutch 95 is retained closed, and whereby the clutch 58 is retained open. When the operation of the staples is completed, by the complete rotation of the shaft 13, the gap 104 assumes 50 a position opposite the roller 98, but at this time the projection 90 on the arm 91 is midway between two of the three equidistant notches of the wheel 89, whereby the arm 91 cannot rise, and whereby the clutch 95 is retained closed and the clutch 58 is retained open. The shaft 13 continuing to rotate, the staple-drivers are then forced downward again, to insert the second row of staples (the sidewise feed-device 88 having shifted the blank sidewise), and this again 55 tilts the lever 74 into the position shown in Figs. 19 and 4, so that the pawl 79 is retracted on the ratchet-wheel 80, and whereby the stop 48 is again raised out of engagement with the pusher 8 (see dotted lines in 60 Fig. 16), but at this time the roller 98 is

held outward by the cylindric periphery of the cam 99, and the arm 91 is held downward by the wheel 89, so that the clutch 95 remains closed and the clutch 58 remains open. After driving the second row of staples, the staple-drivers then reverse their motion and start upward, and during this upward movement the lever 74 is tilted into the position shown in Figs. 20 and 5, so that the ratchet-wheel 80 and the wheel 89 are rotated one notch, thereby bringing one of the notches of the wheel 89 opposite the projection 90, so that the springs 105, which are suitably connected between the arm 93 and some stationary portion of the machine, 70 will rock the shaft 29 backward and thereby close the clutch 58, and whereby the cam 82 is operated to move the rod 85 downward, thus causing the shifter or sidewise feed-device 88 to move away from the feed-belts. 75 The gap 104 in the cam 99 receives the roller 98 and thereby causes the opening of the clutch 95 at about the time the staple-drivers reach the limit of their upward movement, thus opening the clutch 95 and stopping the 80 operation of the staplers. While the staple-drivers are moving upward, after driving the second row of staples, the stop 48 is returning to its lower position, but the relative arrangement of the parts is such, as previously explained, that said stop comes down 85 immediately behind the pusher 8 (see Fig. 14), and this time the clutch 58 closes, thus permitting the feed-belts to move the stapled work ahead and at the same time bring 90 a fresh piece of work into position below the staplers. As soon as the next pusher 8 strikes the stop 48, the clutch 58 will again be opened to interrupt the motion of the feed-belts, and the clutch 95 will be closed to 95 start the operation of the staplers, and the two complete operations of the staplers, as previously described, will then be repeated. When vacant or unoccupied spaces on the 100 feed-belts pass under the roller 52, the latter drops down, and at such time, of course, no staples are driven and the stop 48 is held in such position that the pushers 8 pass under, and the feeding movement is not interrupted until a blank raises the roller 52 and 105 thus lowers the stop 48 into the path of the next pusher. 110

The staplers, of course, can be of any suitable, known or approved character, and are provided with feed-devices 106 for feeding the wire from which the staples are made, these devices being mounted on the transverse shaft 107 arranged behind the staplers. This shaft is provided with a ratchet-feed-device 108 which is operated by the reciprocating pitman 109, the latter being connected with a member 110 which is slotted to reciprocate on the shaft 13, like the device 69, so that both the connection 70 and the pitman 109 move downward when the staple- 115 120 125 130

driver is moved downward. When the pitman 109 moves upward, the ratchet 108 is thereby actuated to operate feed-rolls of the devices 106 for feeding the wire to the 5 staplers. The member 110 has a roller 111 which engages the cam 112 on the shaft 13, (see Fig. 20) so that the pitman 109 is actuated upward by this cam, but a spring 113 is provided and arranged for actuating the 10 pitman 109 downward, thereby to retract the pawl of the ratchet 108 backward over the teeth of the ratchet-wheel. On the other hand, however, the device 69, which is slotted to slide up and down on the shaft 15 13, has a roller 114 which engages in the eccentric groove of the cam 115, whereby the connection 70 is actuated both upward and downward in a positive manner, by said cam 115, thereby to rock the bell-crank 20 37 and the lever 74, in the manner and for the purposes previously described. A band-brake 116, of any suitable character, is applied to the shaft 13, thereby to prevent rotation of this shaft after the clutch 95 is 25 opened, and whereby the staple-drivers will always be stopped in their retracted or highest position.

The guides 23 and 24, it will be seen, are secured to the table by devices 117 which 30 are adjustable along the transverse rows of holes 118 in the top of said table, so that the distance between the guides can be changed or varied at will, thereby to accommodate box-blanks or the like of various 35 widths. As shown in Figs. 8, 9 and 10, the blank of the box is folded in a manner to bring the flat or narrow side-wall 21 immediately above the flap 22, and the first row of staples, it will be seen, is driven 40 along the edge of the flap or side-wall 21, and the second row is driven inside of the first row and through the two thicknesses in such manner that this second row extends longitudinally of the box and parallel with 45 the other row and close to the edge of the inner flap 22, so that the two ends of the blank are connected together by a double row of staples. When the flatwise folded 50 blank is pushed sidewise, by the shifter or sidewise feed-device 88, in the manner previously described, for the driving of the second row of staples, the outer edge of the blank may move over a distance until it engages the guide 24, if the blank is narrower 55 than the distance between the two guides. On the other hand, if the guides have been set to the exact width of the blank when folded flatwise, so that both edges of the blank bear against the guides, the sidewise 60 shifting of the blank will then cause a slight buckling of the sheet-material along the longitudinal fold-lines thereof, at points between the staplers and the outer guide 24, thus permitting the flaps 21 and 22 to assume 65 the desired position for the second row of

staples. Or, as shown, the guide 24 can be formed in two sections, and the section opposite the staplers can be positioned a little farther away from the staplers than the other sections, thus permitting free sidewise 70 shift of the work after the first row of staples is driven. The folded blanks are fed to the receiving end of the machine by hand, and in such manner that the flaps 21 and 22 will properly enter the guide-slots 19 and 20, 75 in the manner previously described. After the driving of the second row of staples, the feed-belts are then automatically started, in the manner explained, and the stapled blank is discharged from the other end of the 80 machine at the same time that another blank or a fresh piece of work is brought below the staplers.

As a matter of convenience for the operator, a foot-pedal 119 is provided at the receiving end of the machine, at the base of the uprights 4, and connected by a pull-rod 120 with the bell-crank 121 pivoted on the body-frame at the other end of the machine. This bell-crank, which has its two arms separated 90 on the rock-shaft 122, is connected by a link 123 with the clutch-shifter 67 which controls the clutch 58 (the spring 124 on the shaft 5 exerts its pressure to close this clutch), so that said clutch can be opened and closed 95 by the attendant or operator at will. This clutch may be of any suitable construction, but should be so adjusted that the feed-belts and the work thereon are stopped in exactly the right position below the staplers, each 100 time the clutch is opened, and so that the feed-belts are controlled properly relatively to the other elements of the machine. As shown, the splined clutch-member which is shifted into engagement with the loose 105 clutch-member, by the spring 124, has some lost motion or rotation on the shaft 5, (the spline *a* being in a notch *b* in the splined member) so that this splined member can turn on the shaft a little, in either direction, 110 if necessary, when the clutch is closed, thus insuring prompt and correct engagement of the teeth on the splined member with the teeth on the loose member, which latter is driven by the power-transmitting connection. 115

It will be understood that any suitable arrangement can be employed for driving the machine. For example, a motor 125 can be employed on one portion of the body-frame 120 and connected by a belt 126 with the pulley 127 on the main drive-shaft 63, which latter extends parallel with the stapler-shaft. To prevent the machine from over-feeding the blanks, and to hold the shaft 5 in position 125 when not rotating, a band-brake 128 is mounted on said shaft 5 and adjusted to operate in the required manner.

What I claim as my invention is:—

1. In a stapling machine, mechanism for 130

inserting fasteners, intermittently operated means to feed the work forward into position below said mechanism to receive a fastener driving operation thereon and devices 5 to thereafter shift the work sidewise into position to receive another operation of said mechanism thereon while said means are stationary, and before the work is again moved forward by said means, whereby the 10 work travels straight ahead and then sidewise and then forward again while passing through the machine.

2. In a stapling machine, as set forth in claim 1, instrumentalities to automatically 15 stop the forward feeding movement and to start the operation of said mechanism, and means to automatically control the operation of said devices.

3. In a stapling machine, as set forth in claim 1, instrumentalities controlled by said means to automatically stop the forward feed and start the operation of said devices, and means controlled by the operation of said mechanism to control the operation of 25 said devices.

4. The machine set forth in claim 1, in which said means are operative to automatically feed the work forward again after the sidewise movement thereof.

5. The machine set forth in claim 1, in which said mechanism is automatically controlled to insert one or more fasteners in the work immediately before and after said sidewise movement thereof.

6. The machine set forth in claim 1, in which said mechanism includes a row of staplers extending parallel with said forward feeding movement and transversely of the direction of said sidewise movement, all in the same horizontal plane.

7. The machine set forth in claim 1, in which said mechanism operates a plurality of times on said work, while said feeding means are stationary, and in which instrumentalities are provided for causing said forward feed and sidewise feed to alternate with the operations of said mechanism, so that the work is held stationary for each operation thereon.

8. In a machine for driving a plurality of parallel rows of staples, the combination of mechanism for inserting the staples, means to feed the work in the direction of said rows, below said mechanism, and a device 55 for shifting the work laterally at right angles to said rows, after the completion of a row, to bring the work into position for the next row, while said means are stationary, and before the work is again moved 60 forward by said means, whereby the work travels straight ahead and then sidewise and then forward again while passing through the machine.

9. The combination of claim 8, whereof 65 said mechanism includes a row of staplers

for inserting the staples simultaneously in each row, so that one operation of said mechanism is sufficient for each row, and in which automatic instrumentalities are provided to discontinue the operation of said feeding means until after the last row is inserted, and to then start the feeding means to convey the finished work away and to bring the next work into position for 75 stapling.

10. The combination of claim 8, whereof said means include feed-belts having pushers for engaging the rear edges of the work, and in which said device includes a horizontally reciprocating member for engaging 80 one side edge of the work to shift the work transversely on said belts, said mechanism including a row of staplers extending parallel with said belts and member.

11. The combination of claim 8, whereof 85 said mechanism has a clutch to control the operation thereof, in which said means have a clutch to control the operation thereof, and instrumentalities controlled by power transmitted through said means to automatically open said first mentioned clutch and close said last mentioned clutch, having automatically controlled provisions to close said first clutch and open the second clutch 90 after the staples are driven in the last row. 95

12. The combination of claim 8, whereof 100 said means include a traveling belt having pushers thereon for engaging the rear edges of the work, so that the successive units of work move forward in a horizontal plane, a movable stop mounted to move into and out of the path of said pushers, and instrumentalities controlled by said stop to automatically interrupt said means and start said mechanism each time a pusher engages said stop.

13. The combination of claim 8, with instrumentalities controlled by said means to automatically discontinue the operation of 110 said means and start the operation of said mechanism, having an operating shaft for said mechanism, and elements actuated by said shaft to operate said device in a horizontal plane.

14. The combination of claim 13, whereof 115 said shaft is provided with a cam arranged to control said instrumentalities and thereby maintain the operation of said mechanism and prevent the operation of said feeding means during the driving of the 120 first row of staples and until after all of the staples are inserted.

15. The combination of claim 13, whereof 125 said elements include a ratchet, a cam operated intermittently by said ratchet, and a connection between said cam and said device.

16. The combination of claim 13, whereof 130 said shaft has a cam, a ratchet operated intermittently by said cam, and a rotary

member associated with said ratchet to control said instrumentalities and thereby maintain the operation of said mechanism and prevent the operation of said feeding means during the interval between the two rows of staples, and until after all of the staples are driven.

17. The combination of claim 13, whereof said instrumentalities include a pivoted stop 10 for engaging said means with a swinging support for said stop, a connection from said shaft to raise said support each time the staples are driven, and devices operated by said shaft to control said instrumentalities and thereby maintain the operation of said mechanism and prevent the operation of said feeding means during the entire stapling of the work and until after the last row of staples is driven.

18. In a stapling-machine, a traveling feed-belt for propelling the work forward, automatically controlled mechanism to intermittently operate said feed-belt, so that each entire unit of work has only one forward feeding movement into staple-receiving position, and means periodically operated by power communicated thereto from said feed-belt to automatically control said mechanism.

19. The structure of claim 18, said means comprising a pivoted stop, a roller connected to control said stop and arranged to bear upon the upper surface of the work, so that said roller has up and down movement, a movable support for said stop, said feed-belt having a series of elements to successively engage said stop, and means to raise said support a distance during each operation of said machine.

20. In a stapling-machine, a traveling feed-belt for propelling the work forward, stapling-mechanism, means periodically operated by power communicated thereto from said feed-belt to automatically start and stop the operation of said mechanism.

21. The structure of claim 20, said means comprising a pivoted stop, a roller connected to control said stop and arranged to bear upon the work, so that the stop and roller swing about a transverse axis, a movable support for said stop, said feed-belt having a series of elements to successively engage said stop, and means to raise said support a distance during each operation of said machine.

22. In a stapling machine, a row of automatically controlled staplers, a bar extending under said staplers to clench the staples, so that the staples are simultaneously clenched at intervals along the length of said bar, means for guiding the work in a direction longitudinal of said bar and row of staplers, so that portions of the work will travel forward above and below the bar, and automatically controlled traveling means to feed the work along said guiding means, in combi-

nation with means to automatically shift the work sidewise and transversely of said bar, to permit the successive driving of parallel rows of staples, so that for each unit of work said staplers are only operated as many times as there are rows of staples required therefor.

23. In a stapling machine, a row of automatically controlled staplers, a bar extending under said staplers to clench the staples, so that the staples are simultaneously clenched at intervals along the length of said bar, means for guiding the work in a direction longitudinal of said bar and row of staplers, so that portions of the work will travel forward above and below the bar, and automatically controlled traveling means to feed the work along said guiding means, in combination with devices to automatically interrupt the operation of said traveling means, mechanism to operate said staplers a plurality of times during each stand-still of said traveling means, and devices to automatically shift the work sidewise while said traveling means are stationary, so that the rows of staples are spaced apart the proper distance.

24. In a stapling machine, mechanism for inserting fasteners, means to feed the work forward below said mechanism, and devices to feed the work sidewise below said mechanism, including instrumentalities controlled by said means to automatically stop the forward feed and start the operation of said devices, and means controlled by the operation of said mechanism to control the operation of said devices.

25. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, said mechanism including a row of staplers for inserting the staples simultaneously in each row, so that one operation of said mechanism is sufficient for each row, and automatic instrumentalities to discontinue the operation of said feeding means until after the last row is inserted.

26. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, said means including feed-belts having pushers for engaging the rear edges of the work, and said device including a reciprocating member for engaging one side edge of the work to shift the work

transversely on said belts, said mechanism including a row of staplers extending parallel with said belts and member.

27. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, said mechanism having a clutch to control the operation thereof, said means having a clutch to control the operation thereof, and instrumentalities controlled by power transmitted through said means to automatically open said first mentioned clutch and close said last mentioned clutch, having provisions to close said first clutch 20 and open the second clutch after the staples are driven in the last row.

28. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, said means including a traveling belt having pushers thereon for engaging the rear edges of the work, a movable stop mounted to move into and out of the path of said pushers, and instrumentalities controlled by said stop to automatically interrupt said means and start said mechanism each time a pusher engages said stop.

29. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, together with instrumentalities controlled by said means to automatically discontinue the operation of said means and start the operation of said mechanism, having an operating shaft for said mechanism, and elements actuated by said shaft to operate said device.

30. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, together with instrumentalities controlled by said means to automatically discontinue the operation of said means and start the operation of said mechanism, having an operating shaft for said mechanism,

and elements actuated by said shaft to operate said device, said shaft being provided with a cam arranged to control said instrumentalities and thereby maintain the operation of said mechanism and prevent the operation of said feeding means during the driving of the first row of staples.

31. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, together with instrumentalities controlled by said means to automatically discontinue the operation of said means and start the operation of said mechanism, having an operating shaft for said mechanism, and elements actuated by said shaft to operate said device, said elements including a ratchet, a cam operated by said ratchet, and a connection between said cam and said device.

32. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, together with instrumentalities controlled by said means to automatically discontinue the operation of said means and start the operation of said mechanism, having an operating shaft for said mechanism, and elements actuated by said shaft to operate said device, said shaft having a cam, a ratchet operated by said cam, and a rotary member associated with said ratchet to control said instrumentalities and thereby maintain the operation of said mechanism and prevent the operation of said feeding means during the interval between the two rows of staples.

33. In a machine for driving a plurality of parallel rows of staples, the combination of mechanism for inserting the staples, means to feed the work in the direction of said rows, below said mechanism, and a device for shifting the work laterally at right angles to said rows, after the completion of a row, to bring the work into position for the next row, together with instrumentalities controlled by said means to automatically discontinue the operation of said means and start the operation of said mechanism, having an operating shaft for said mechanism, and elements actuated by said shaft to operate said device, said instrumentalities including a pivoted stop for engaging said means, with a swinging support for said stop, a connection from said shaft to

raise said support each time the staples are driven, and devices operated by said shaft to control said instrumentalities and thereby maintain the operation of said mechanism and prevent the operation of said feeding means until after the last row of staples is driven.

34. In a stapling-machine, a traveling feed-belt for propelling the work forward, mechanism to intermittently operate said feed-belt, and means periodically operated by power communicated thereto from said feed-belt to automatically control said mechanism, said means comprising a pivoted stop, a roller connected to control said stop and arranged to bear upon the work a movable support for said stop, said feed-belt having a series of elements to successively engage said stop, and means to raise said support a distance during each operation of said machine.

35. In a stapling-machine, a traveling feed-belt for propelling the work forward, stapling mechanism, and means periodically operated by power communicated thereto from said feed-belt to automatically start the operation of said mechanism, said means comprising a pivoted stop, a roller connected to control said stop and arranged to bear upon the work, a movable support for said stop, said feed-belt having a series of elements to successively engage said stop, and means to raise said support a distance during each operation of said machine.

36. In a stapling-machine, a row of staplers, a bar extending under said staplers to clench the staples, guides for feeding the work upon and under said bar, in a direc-

tion longitudinal of said bar and row of staplers, and traveling means to feed the work to said guides, in combination with means to automatically shift the work sidewise and transversely of said bar, to permit the successive driving of parallel rows of staples.

37. In a stapling-machine, a row of staplers, a bar extending under said staplers to clench the staples, guides for feeding the work upon and under said bar, in a direction longitudinal of said bar and row of staplers, and traveling means to feed the work to said guides, in combination with devices to automatically interrupt the operation of said traveling means, mechanism to operate said staplers a plurality of times during each standstill of said traveling means, and devices to automatically shift the work sidewise while said traveling means are stationary.

38. In a power-transmitting connection, a shaft provided with a loose clutch member and a splined clutch member, the splined clutch member having means to permit partial rotation thereof on the shaft, when the two members are forced together, mechanism to rotate the loose member, and devices to shift the splined member into and out of engagement with the loose member, in combination with work-feeding means operated by said shaft, staplers to operate on the work, and means to automatically control said devices, so that the clutch is automatically opened and closed.

Signed by me at Chicago, Illinois, this 11th day of April, 1917.

EDWARD CRAIG.
